JET DEVICE

Filed July 20, 1929

FIG. 1

INVENTOR:
Howard D. Yoder

CHARLES J. BELL
ATTORNEY

UNITED STATES PATENT OFFICE

HOWARD D. YODER, OF DETROIT, MICHIGAN, ASSIGNOR TO PENBERTHY INJECTOR COMPANY, OF DETROIT, MICHIGAN, A CORPORATION OF DELAWARE

JET DEVICE

Application filed July 20, 1929. Serial No. 379,599.

This invention relates to jet action and particularly to jet actions of the automatic overflow type wherein a jet is automatically established after interruption of water supply during the working cycles of the jet.

The automatic reestablishing feature resides in a provision of large relief spaces or openings so that before a mixture of steam and water has reached proper proportions the improperly mixed jet can escape through the overflow valve before the jet is established in its normal or working proportions. The steam and water flow alternately into the jet until the jet itself is established. Spillage is allowed during the formation of the jet and is stopped when the jet is formed, that is, when the steam and water have reached proper proportions for the working range of the structure. The relief space is thereby reduced to a minimum for the working range of the device.

The invention contemplates a delivery tube including several slidable sections one of which is responsive to the pressure created in the delivery chamber so as to be moved axially by such pressure and it in turn moves another of the sections to reduce the relief zone or area as the first section is moved responsive to the pressure in the delivery chamber.

This invention provides for a large relief space for starting the jet or injector action and contemplates the provision of several large spaces communicating with the overflow of the device and including slidable sections which when moved responsive to the pressure in the delivery chamber constitute the delivery tube of the jet structure.

Spill holes may be provided in the movable sections for providing additional relief space for the escape of fluid before the flow is established in its normal or working proportions.

The large relief spaces are required for automatic starting but are not efficient after the jet has been established to allow the same to operate at maximum efficiency. Internal pressure in the device causes discharge of some water which may be through the spill holes and which eventually escapes through

the overflow opening, such overflow admitting some air to the combining chamber thereby affecting the vacuum established in this chamber. It is therefore desirable to provide means for reducing the large starting area or zone as the jet is formed or established to allow operation of the jet through a wide range. 55

An object of the invention is to provide a jet or jet action in which large spillage areas are provided for starting and which are eliminated or reduced to working range after the jet is established. 60

Another object of the invention is to provide a jet action wherein large spillage areas 65 are created at the outset and eliminated by the action of the jet itself.

A further object of the invention is to provide a jet action wherein large starting spaces or areas are provided and which spaces are reduced after the jet is established by building up pressure in the delivery chamber, which pressure serves to move certain parts of the structure to reduce the starting spaces. 70

Another and still further object of the invention is to provide a jet action wherein large spillage areas are provided for starting purposes and which spillage areas are eliminated after the establishment of the jet by building up pressure in the delivery chamber wherefor the action of the jet itself serves to reduce such starting or spillage areas. 75

A yet further object of the invention is to provide a jet action with a delivery tube comprising severable slidable sections. 85

A still further object of the invention is to provide a jet action of the single tube automatic overflow type arranged to automatically reestablish the jet after interruption of water supply during the working cycle of the jet and which jet action is economical to manufacture and efficient in operation over a wide range. 90

The above, other and further objects of the invention will be apparent from the following description, accompanying drawings and appended claims. 95

An embodiment of the invention is illustrated in the accompanying drawings and the views thereof are as follows: 100

Figure 1 is a axial sectional view of a jet device of the injector type embodying the present invention and showing the delivery tube as constituting two slidable sections as the same appear when the jet is inoperative or at the time the action has started and before the jet is established.

Figure 2 is a fragmental sectional view of a portion of the apparatus of Figure 1 showing the delivery tube sections as the same appear in operation when a jet is established.

The invention is illustrated herein in connection with an injector and shows the delivery tube as consisting of two sliding sections. It is to be understood at the outset that the invention is not limited to an injector but is susceptible of use in any situation wherein jet action is utilized. It is further to be understood that the delivery tube is not limited to two sliding sections but may be made up of as many sliding sections as conditions warrant.

The invention will, for the sake of brevity, be hereinafter referred to as an injector, however, such term is used generically and not by way of limitation and when so used is to be understood as contemplating jet action of any kind whatsoever and therefore its use in the appended claims should be construed accordingly.

The injector, as illustrated, includes a longitudinally sectioned casing 1 each section of which is formed with cooperating partitions 2, 3, 4, 5 and end walls 6 and 7, defining respectively a water and steam chamber A, a combining chamber B, supplemental combining chambers C and D, a delivery chamber E and an overflow chamber F. The sections of the casing 1 are provided with co-acting flanges bolted or otherwise secured together.

The casting is provided with a steam inlet orifice 8, a water inlet orifice 9, a boiler discharge outlet 10 and an overflow outlet 11.

A steam inlet nozzle 12 is secured in the steam inlet orifice 8 in any suitable manner and projects into the water and steam chamber A. A nipple 13 is connected by means of a collar 14 to the steam inlet end of the apparatus for connection to a steam supply line.

A nipple 15 is shown as secured by a collar 16 to the water inlet 9.

A nipple 17 is connected by means of a suitable connector 18 to the boiler outlet 10, while the overflow outlet 11 is connected by means not shown to a waste pipe.

The partition 2 has an axial opening 19 in which is secured a nozzle 20 which has a tapered bore therethrough converging from the entrance to the discharge end of the nozzle. A packing ring or gasket 20a is positioned between the walls of opening 19 and the outer walls of nozzle 20 to provide a liquid-tight joint therebetween.

The bore of the steam nozzle 12 is shown as cylindrical at 21 and as diverging at 22.

The partition 3 likewise has an axially disposed opening 23 through the same. The partitions 4 and 5 also have axial openings 24 and 25 in the same.

A nozzle 26 is arranged for sliding movement in the opening 23 of the partition 3 and is provided with a shoulder 27 to limit movement thereof in one direction. The diameter of the nozzle 26 is slightly smaller than the diameter of the opening 23 through the partition 3. It is, of course, presumed that the shape of the outer surface of the nozzle 26 and the corresponding shape of the opening 23 in the partition 3 may be circular or of any other shape and therefore the use of the term "diameter" is meant to include size where these shapes are other than circular.

The nozzle 26 has a converging bore 28 through the same converging in the direction of flow.

The nozzle member 29 is slidably supported within the apertures 24 and 25 of the partitions 4 and 5 respectively and extends beyond the outer surfaces of each of these partitions. The nozzle 29 has a bore through the same, the portion of the bore at the entrance end being converging as at 30 with an intermediate cylindrical portion 31 and a diverging delivery end portion 32. The nozzle also has an outer circumferential shoulder 33 provided with a plurality of spillage passages 34 communicating with the cylindrical bore 31 of the nozzle.

The outer diameter of the end of the nozzle 29 where the same passes through the aperture 24 in the partition 4 is slightly smaller than the diameter of said aperture. Likewise the diameter of the other end of the nozzle 29 is smaller than the diameter of the aperture 25 in the partition 5. Shoulders 35 are provided on the nozzle 29 for resting against the upper surface of the partition wall 5.

It might be said here that the illustrated form of the invention is shown in connection with a vertically acting injector, but, of course, the invention is susceptible of use with a horizontally or otherwise disposed device. Reference to upper and lower in this specification should be construed in accordance with the drawings and construed as being merely illustrative of the illustrated form of the invention and not as limitations of the same.

The overflow chamber F is normally closed by a valve 36 which is carried on an arm 37 pivoted at 38 to the casting so that the valve 36 may swing away from its seat to allow spillage into the overflow connection 11 for disposal. The casing is provided with a plug 39 whereby access may be had to the overflow valve 36. A plug 40 closes the lower end of the delivery chamber E and is utilized for purposes well understood. The plug 40 is hollow so as to enlarge the capacity of the delivery chamber E as the jet is forming and

also as the jet operates in its working cycle.

The normal position of the sliding nozzles 26 and 29, that is, when the device is inoperative or at the time the jet action is started, is as illustrated in Figure 1, such arrangement providing gaps G and H.

The operation of the illustrated form of the invention is as follows:

The arrangement of parts shown in Figure 1 shows the position of the same when steam is flowing from the nozzle 12 and exhausting through the gap H to the overflow chamber F. The passage of the steam draws with it water and the steam and the water for a time are uncombined in the proper proportions for forming the jet. Surplus of water and steam pass from the gaps G and H into the overflow chamber for discharge and any excess steam and water delivered to the nozzle 29 will to some extent pass outwardly through the opening 34 and upwardly through the space between the aperture 24 in the partition 4 and the upper end of the nozzle 29 to the overflow chamber F. After the flow has become better established steam ceases to flow from the nozzle 20 and the water from the water supply 15 and the condensed steam now pass from the nozzle 12 through the nozzle 20 through the sections 26 and 29 into the delivery chamber where pressure is built up, lifting the nozzle 29 to the position shown in Figure 2. The nozzle 29 will as soon as it has been lifted a distance equal to the gap G contact the nozzle 26 and in turn lift it, thus reducing the gap H to that shown in Figure 2 which is in effect a mere normal clearance gap between the nozzle 20 and the nozzle 26 which now becomes the upper end of the delivery tube. A jet is formed or established by this time and the nozzles 26 and 29 form the delivery tube and remain in this position until the water supply is for some reason interrupted. It will be observed that by the action just described the gap G has disappeared entirely and that the gap H has been reduced to a mere normal clearance gap. Furthermore, the engagement of the shoulder 33 with the underside of the partition 4 closes escape to the overflow chamber F from the spill holes 34.

It will be observed that by the operation just described relief spaces are provided at the gaps G and H and also through the spill holes 34 for spillage action while the jet is forming and that when the jet is formed or established the gap G is eliminated as is also discharge from the spillage holes 34 while the gap H is reduced to a nominal operating range.

The bore of the nozzle 26 conforms to the inclination of the bore 30 of the nozzle 29 so that when the nozzles 26 and 29 are in end-wise contact as illustrated in Figure 2 the convergence of the bore 28 of the nozzle 26

and the bore 30 of the nozzle 29 will be continuous.

The discharge end of the bore of the nozzle 20 has a cylindrical portion 41 for the purpose of forming the flowing stream into a cylindrical shape to bridge the gap H for reducing friction against the receiving end of the bore 28 of the nozzle 26, thereby lengthening the life of usefulness of the device.

The invention has been described herein more or less precisely yet it is to be understood that the same is not to be limited thereby as it is understood that changes may be made in the arrangement and proportion of parts and that equivalents may be substituted without departing from the spirit and scope of the invention.

The invention is claimed as follows:

1. A jet device or injector of the automatic open overflow type having a plurality of sliding nozzle sections constituting a delivery tube, said sections defining gaps between the same when separated, said gaps providing spillage areas, one of said sections being responsive to the pressure created by the established jet for moving said tube against another of said sections for varying the gaps.

2. A jet device or injector having a plurality of separate relatively slidably axially spaced nozzle sections constituting a delivery tube, said separated nozzles forming gaps between the same, one of said sections being movable responsive to the pressure created by the established jet, said one section moving another section to vary the gap between it and an adjacent section.

3. A jet device or injector including a plurality of axially spaced nozzle sections, some of said sections being axially movable, said spaced sections forming gaps between the same, said injector having an overflow chamber in communication with said gaps, one of said nozzle sections being movable in response to the pressure created by the established jet to close the gap between it and the next section and move said next section to vary the gap between it and the next adjacent section.

4. A jet device including a plurality of axially movable sections forming a delivery tube, a delivery chamber into which one of said movable sections projects, said movable sections being moved axially away from said delivery chamber by pressure created therein by jet action for reducing the spaces between said several movable sections.

5. A jet device or injector of the automatic open overflow type comprising a casing, a fixed combining nozzle in said casing, a plurality of aligned nozzles slidably mounted in said casing and constituting a delivery tube, all of said nozzles being spaced apart to provide spillage gaps therebetween when the injector is starting, compartments in said cas-

ing into which said spillage gaps discharge, another compartment in said casing surrounding the outermost of said delivery nozzles, said last named nozzle having spill openings leading to said surrounding compartment, an overflow chamber in communication with all of said compartments, said outermost delivery nozzle being movable under the pressure created by the established jet when the injector is started to close the gap between it and the next adjacent nozzle and move said next nozzle toward said combining nozzle to decrease the spillage gap therebetween and means on said outermost delivery nozzle for cutting off communication between the overflow chamber and the compartment surrounding said outermost delivery nozzle when said nozzle is moved toward combining tube.

20 In testimony whereof I have hereunto subscribed my name at Detroit, Wayne County, Michigan.

HOWARD D. YODER.
